US00D804515S

(12) **United States Design Patent** (10) **Patent No.:** **US D804,515 S**
(45) **Date of Patent:** **** Dec. 5, 2017**

(54) **DISPLAY SCREEN OR PORTION THEREOF
WITH GRAPHICAL USER INTERFACE**

(71) Applicant: **TD Bank, NA**, Cherry Hill, NJ (US)

(72) Inventors: **Vinoo Vijay**, Philadelphia, PA (US);
Samrat Joshi, Philadelphia, PA (US);
Amar Ghai, Philadelphia, PA (US);
Daniel Brewin, Philadelphia, PA (US)

(73) Assignee: **TD Bank, NA**, Cherry Hill, NJ (US)

(**) Term: **15 Years**

(21) Appl. No.: **29/580,000**

(22) Filed: **Oct. 5, 2016**

(51) **LOC (10) Cl.** **14-04**

(52) **U.S. Cl.**

USPC **D14/487**

(58) **Field of Classification Search**

USPC D14/485-495; D12/192; D20/11;
D21/324, 325

CPC G06F 3/04817; G06F 3/0482; G06F
3/04842; G04G 9/04; B63J 99/00; G09G

5/363; A61M 25/10182; F24F 11/0086

See application file for complete search history.

(57) **CLAIM**

The ornamental design for a display screen or portion thereof with graphical user interface, as shown and described.

DESCRIPTION

The FIGURE is a front view of a display screen or portion thereof with graphical user interface showing our new design,

The broken line showing of the remainder of the graphical user interface and the remainder of the display screen is for environmental purposes only and forms no part of the claimed design.

The dot-dash lines define the bounds of the claimed design and form no part thereof.
